ISOMERIZATION

Winfield Scott, deceased, late of Akron, Ohio, by
Ruth P. Scott, executrix, Akron, Ohio, assignor
to Wingfoot Corporation, Akron, Ohio, a corpora-
tion of Delaware

No Drawing. Application August 9, 1943,
Serial No. 497,972

6 Claims. (Cl. 260—485)

1

This invention relates to the isomerization of alpha-beta unsaturated acids and esters from the cis to the trans form. The invention lies in the use of a conversion agent, without which no detectable conversion occurs. The invention includes the isomerization of such compounds in which one or more of the hydrogens connected directly to a carbon atom have been replaced by chlorine, alkyl or other substituent. The ester may be an alkyl ester, such as methyl, ethyl, propyl, etc., or an aralkyl ester, such as benzyl, etc. It includes the isomerization of angelic-acid esters to tiglic-acid esters; cinnamic esters from the cis to the trans isomer; chlormaleic-acid esters to chlorfumaric-acid esters; citraconic-acid esters to mesaconic esters; crotonic-acid esters from the cis to the trans isomer; etc.

According to this invention, the isomerization is effected in the presence of an isomerizing agent which contains the grouping

in which the linkage between C and S or C and N may be a single or double bond. Representative examples of such isomerizing agents, which include the thiazoles, thiazolines, thiuram disulfides, etc., are:

(1)

2-mercaptopbenzothiazole

(2)

Benzothiazyl disulfide

(3)

2-mercaptopthiazoline

(4)

2-mercaptop-4-methylthiazole

2

5

Methylol-2-mercaptop-4-methylthiazole

6

Tetramethyl thiuram disulfide

10

Piperidinium N,N-pentamethylene dithiocarbamic acid

The invention will be illustrated by the following examples:

Example 1

20 A mixture of 15 grams of diethyl maleate and 0.3 gram of 2-mercaptop-4-methylthiazole was heated in an oil bath at about 140° C. Every five minutes, a 0.4 ml. sample was withdrawn and mixed with 0.6 ml. of Nujol. The consolute temperature of this mixture was determined, and from it, the percentage of diethyl fumarate in the reaction mixture was calculated. The results are given below:

30	Time	Consolute	Per cent diethyl fumarate
		temp., ° C.	
Just after mixing		104.25	-----
After heating to 140°		95.25	12
5 minutes at 140°		80.50	30
10 minutes at 140°		69.25	44
15 minutes at 140°		58.25	57
20 minutes at 140°		48.25	70
25 minutes at 140°		41.50	78
30 minutes at 140°		37.00	83
35 minutes at 140°		35.25	85

40

Example 2

45 A mixture of 5 grams of monomethylmaleate and 0.1 gram of 2-mercaptopthiazoline was heated at about 140° C. for one hour. The mixture darkened considerably during this time, but on cooling, monomethyl fumarate crystallized out. Weight of product, 2.1 grams (42 per cent).

Example 3

50 Two and a half grams of 2-mercaptop-4-methylthiazole were dissolved in 85 grams of water, and 100 grams of maleic anhydride were added. The mixture was heated at its boiling point with stirring for about 2.5 hours. Upon cooling, the solution yielded 90 grams of fumaric acid. Further

heating for 4 hours and distilling off most of the water resulted in the separation of an additional 22 grams of fumaric acid. Total yield, 95 per cent.

Example 4

A mixture of 15 grams of diethyl maleate and

The following table indicates the extent of the conversion, using different isomerizing agents at different temperatures, with the approximate time required for the conversion, and in several instances the results are compared with those obtained with known isomerizing agents:

Derivative converted	Agent	Time, hrs.	Temp., ° C.	Per cent conversion
Maleic acid	2.2% potassium thiocyanate	2.25	109-101	89
Do	1.7% 2-mercaptopbenzothiazole	2.0	109-101	77
Do	2.3% 2-mercaptopthiazoline	4.0	109-101	88
Do	2.1% 2-mercaptop-4-methylthiazole	2.5	109-101	76
Do	2.1% 2-mercaptop-4-methylthiazole	6.5	109-101	95
Monomethyl maleate	2% 2-mercaptopthiazoline	1.0	140	42
Dimethyl maleate	0.5% iodine	2.5	190	89
Do	1% 2-mercaptop-4-methylthiazole	0.5	160	75
Diethyl maleate	1% iodine	1.0	160	36
Do	1% 2-mercaptopbenzothiazole	1.0	160	60
Do	1% 2-mercaptop-4-methylthiazole	1.0	160	98
Do	1% methylol-2-mercaptop-4-methylthiazole	1.0	160	98
Do	1% cyclohexylamine derivative of zinc thiofuroate	0.5	160	16
Do	1% tetramethyl thiuram disulfide	1.0	160	79
Do	1% benzothiazyl disulfide	1.0	160	13
Do	1% piperidinium pentamethylene dithiocarbamic acid	1.0	160	41
Do	1% 2-mercaptopquinoline	1.0	160	63

0.15 gram of 2-mercaptopbenzothiazole was heated at about 160° C. for one hour. A determination of the consolute temperature revealed that 60 per cent of the maleic ester had been converted to the fumarate ester.

Example 5

A mixture of 5 grams of diethyl maleate and 0.025 gram (0.5 per cent) 2-mercaptop-4-methylthiazole was heated at about 120° C. for 80 minutes. Thirty-two per cent of the ester was converted to the fumarate.

Example 6

Two grams of 2-mercaptopbenzothiazole were dissolved in 66.5 grams of water, and 118.5 grams of maleic acid were added. This mixture was heated at its boiling point with stirring for about 2 hours. The solution was cooled, and the fumaric acid which separated was filtered off, dried, and weighed. Yield, 91.5 grams (77 per cent)

In determining the percentage of the transform of an alpha beta unsaturated acid or ester prepared in accordance with the process of this invention, a mixture of Nujol (a special type of mineral oil) and a sample of the reaction mixture resulting from the heating of the alpha beta unsaturated acid or ester with any of the suitable isomerizing agents of this invention, is heated to about 120° C. (or some temperature higher than the consolute temperature of the mixture) and then the heated mixture is allowed to cool and the temperature at which the mixture just begins to become clouded is observed and is referred to as the consolute temperature. This temperature is referred to a chart (on which is plotted a series of consolute temperatures and corresponding conversion percentages obtained from known mixtures) and the corresponding percentage conversion obtained.

Other conversion agents include: 2-mercaptopthiazole, thiazyl disulfide, 4-methylthiazyl disulfide, tetraethyl thiuram disulfide, tetraethyl thiuram disulfide, methylol-2-mercaptopbenzothiazole, methylol-2-mercaptopthiazole, dipentamethylene thiuram disulfide, diethyl ammonium diethyl dithiocarbamic acid, etc.

What is claimed is:

1. The process of isomerizing diethyl maleate to the diethyl fumarate which comprises the step of heating the maleate in the presence of 2-mercaptop-4-methyl thiazole at a temperature of about 140° C. until conversion is substantially complete.

2. The process of isomerizing dialkyl maleates which comprises heating the dialkyl maleate in the presence of tetramethyl thiuram disulfide.

3. The process of isomerizing dialkyl maleates which comprises heating the dialkyl maleate in the presence of 2-mercaptop-4-methyl thiazole.

4. The process of isomerizing diethyl maleate which comprises heating the compound in the presence of 2-mercaptop-4-methyl thiazole.

5. The process of isomerizing dialkyl maleate which comprises heating the dialkyl maleate in the presence of a catalyst from the group consisting of 2-mercaptopbenzothiazole, 2-mercaptopthiazoline, 2-mercaptop-4-methyl thiazole, methylol-2-mercaptop-4-methyl-thiazole, tetramethylthiuram disulfide, 2-mercaptopthiazole, thiazyl disulfide, 4-methyl thiazyl disulfide, tetraethyl thiuram disulfide, methylol-2-mercaptopthiazole, dipentamethylene thiuram disulfide and diethyl ammonium diethyl dithiocarbamic acid.

6. The process of isomerizing a dialkyl maleate which comprises heating the dialkyl maleate in the presence of 2-mercaptopbenzothiazole.

RUTH P. SCOTT,
*Executrix of the Last Will and Testament of
Winfield Scott, Deceased.*
